BEDSPREAD RACK

Margaret A. Volk, Toledo, Ohio

Application November 7, 1949, Serial No. 5,923

Term of patent 3½ years

(Cl. D33—8)

To all whom it may concern:

Be it known that I, Margaret A. Volk, a citizen of the United States, and resident of Toledo, in the county of Lucas and State of Ohio, have invented a new, original, and ornamental Design for a Bedspread Rack, of which the following is a specification, reference being had to the accompanying drawing, forming a part thereof.

In the drawing, Fig. 1 is a perspective view of a bedspread rack showing my new design, and Fig. 2 is a side elevation thereof.

I claim:

The ornamental design for a bedspread rack, substantially as shown.

MARGARET A. VOLK.
